ATTORNEY.

UNITED STATES PATENT OFFICE.

BEN K. FORD, OF OAK PARK, ILLINOIS, ASSIGNOR TO FIBRE CAN CORPORATION, OF CHICAGO, ILLINOIS, A CORPORATION OF ILLINOIS.

CONTAINER HEADER.

Application filed December 3, 1920. Serial No. 428,119.

To all whom it may concern:

Be it known that I, BEN K. FORD, a citizen of the United States, and residing at Oak Park, in the county of Cook and State 5 of Illinois, have invented a new and Improved Container Header, of which the following is a specification.

This invention relates to means for attaching sheet metal heads or ends to paper 10 or other fibrous bodies of containers, or cans as they are usually called, and its object is to provide a simple and effective machine of this character which can be readily and quickly adapted to containers 15 of any desired cross section.

This invention consists, in combination with rotatable means for supporting the container including a mandrel adapted to fit into the usual depressions in the heads, 20 of a roller to crimp the edges of the container heads downward and inward, and means for causing the roller to follow a path which is parallel to the walls of the container.

25 This invention further consists in a guide block provided with a guide groove, a pair of arms pivoted on the machine, one of which carries the crimping roller and the other a guide roller which travels in 30 the groove in the guide block, and means for causing angular movement between said arms.

This invention further consists in providing a wedge which is so carried that 35 it may swing with the arms carrying the guide and crimping rollers and be movable between said arms so as to force the crimping roller toward the container.

It also consists in the details of construction illustrated in the accompanying drawings and particularly pointed out in the 40 claims.

In the drawings, Fig. 1 is a side elevation and Fig. 2 is a front elevation of this 45 improved container header. Figs. 3 and 4 are sections on the lines 3-3 and 4-4 of Fig. 1 respectively. Fig. 5 is a section on the line 5-5 of Fig. 3. Fig. 6 is a side elevation of the crimping arm and the guide 50 mechanism therefor. Fig. 7 is a section of a portion of a container showing the manner of attaching the top.

Similar reference characters refer to like 55 parts throughout the several views.

The machine shown in the drawings is

mounted on a base 1 supported by legs 2 and the pedestal 3 having upwardly extending arms 4 and 5 which support bearings for the main shaft 6. On one end of this shaft is a gear 7 meshing with the gear 60 8 on the spindle 9, journaled in the bearings 10 and 11. On the lower end of this bearing 11 is the guide block 12 and the mandrel 13 is the lower end of the spindle. Adjustably mounted on the pedestal is 65 a guide bracket 14 for the vertically mounted post 15 which carries collars 16 to limit the upward movement of the post and to receive the thrust of the spring 17 which receives this thrust from the slide- 70 ble collar 18 mounted in the forked front end of the lever 19. The post 15 has a central hole to receive the stem 20 which may rest on a ball 21. A table 22 to support the container bodies is attached to the 75 upper end of the stem 20 and rotates with the containers as they are turned by the spindle 9 and the mandrel 13.

Any desired clutch drive may be employed to rotate the shaft 6. I have shown 80 the pulley 25 rotatable on the shaft and it may be driven in any desired manner and is constructed to fit the clutch cone 26 which is slidable on the shaft and connected thereto by a feather 27. A pin 29 85 is centrally mounted in this shaft and engages the cross pin 28 which is mounted in a slot in the shaft so that when this pin is forced forward, the cone 26 is forced into the pulley 25 to cause this pulley to 90 drive the shaft.

The foot pedal 31 mounted on the rod 32 carries a pin 33 on which the link 34 is mounted. This link connects to the lever 19 and to the second link 35, which, in 95 turn, connects to the vertically slidable bar 36 guided by the arms 4 and 37. These parts are normally held up by the spring 38. On the bar 36 is mounted a cam block 39 which engages the pin 29 and forces it 100 inward sufficiently to cause engagement of the clutch when the pedal 31 is depressed. The block 39 is long to permit completion of the movement of the other parts connected to the pedal. Any other desired 105 means to drive the shaft 6 may be employed.

The mandrel 13 is provided with a plate 41 at its lower end which fits within the head of the container, the head 42 being usually formed with an upstanding and 110

then laterally projecting flange 43, as shown in Fig. 7, and the object of this machine is to turn the outer edge of the flange in against the body 44 of the container. As 5 the mandrel is rotated, the container 44 and the small table 22 rotate with it.

The shape of the plate 41 on the lower end of the mandrel is that of the cross section of the container 44, but it is a trifle 10 smaller to allow for the thickness of the metal of the head. The flange 43 is curled over by a roller 46 of well known form mounted on a pin 47 on the arm 48, which arm is mounted on a vertical shaft 49 (Fig. 15 3) carried by the arms 50 and 51 that extend from the pedestal 3. See Fig. 6.

A second arm 53 is also mounted on this shaft and carries a pin 54 on which the guide roller 55 is mounted, and this roller extends 20 up into the groove 56 in the guide block 12, which groove is of such a form that the pin 54 travels in a path which is substantially a reproduction of the periphery of the curled-over edge of the container head shown in 25 Fig. 7. This cam groove may be of any desired form, depending on the cross section of the container body to be headed, which may have any number of sides or be of any desired cross section. The two arms 48 and 30 53 are drawn toward each other by the spring 58.

A third arm 59 is mounted on this vertical shaft 49 and in its free end is slideable a stem 60 which is normally held up by the 35 spring 62. On this stem is a wedge 63 adapted to extend down between the arms 48 and 53 as shown in Fig. 5, the lower arm having a lug 64 to give a bearing to the wedge in alignment with the upper arm. A hook 65, 40 a thin flexible strap 66, a clamp 67 and a screw-threaded rod 68 slideable in the pin 33 and threaded into the clamp 67 constitute the connection between this wedge and the pedal 31.

45 The operation of this mechanism is as follows: When the pedal 31 is released it is elevated by the spring 38 which lifts the cam block 39 out of engagement with the pin 29 and thus permits the clutch to disengage.

50 At the same time the post 15 slides down and with it the table 22 and the container, which may then be removed and be replaced with another, on the upper end of which a head 42 has been placed. The pedal 31 is 55 then depressed, which causes the table 22 and the container to be elevated and the head 42 to be pressed against the mandrel, the plate 41 fitting down in the depression within the flange 43 of the container head. Continued movement of the pedal compresses the 60 spring 17 and also moves down the cam block 39, which causes the pedal 9 and the mandrel 13 together with the container and the supporting table 22 to rotate.

65 At this time the pin 33 engages the head

70 of the screw 68 and pulls down the flexible strap 66, which causes the wedge 63 to force the arm 48 and the crimping roller 46 against the laterally projecting flange 43 of the container head. With the exception of 70 this lateral movement caused by the wedge 63, the two arms 48 and 53 move together and as the roller 55 is traveling in the cam groove 56 the crimping roller 46 follows the outer surface of the container 44 and evenly 75 and gradually curls the edge of the flange 43 inwardly to the position shown in Fig. 7. The guide block 12 in Fig. 3 is shown provided with a cam groove 56 adapted for containers which are rectangular in cross 80 section, but this guide block may be replaced by others with any desired cam grooves so that the machine may be adapted for containers of any desired cross section and size by merely substituting new plates 41 and 85 guide blocks 12.

The details of the operating and driving mechanism, and the proportions of the parts may all be changed by those skilled in the art without departing from the spirit of my invention as set forth in the following claims.

I claim:

1. In a machine for securing heads to container bodies, the combination of means for rotating the container body with the head thereon, a crimping roller adapted to be pressed against the edge of the head to curl it against the container body, an arm to carry said roller, means to cause the crimping roller to travel in a path parallel 100 to the wall of the container body, said means comprising a guide block provided with a cam groove, a pivoted arm and a roller in the end thereof extending into the cam groove, and means for communicating the movement of said pivoted arm to the crimping roller comprising a wedge between said arms and a pedal to actuate the wedge.

2. In a machine for securing heads to container bodies, the combination of means 110 for rotating the container body with the head thereon, a crimping roller adapted to be pressed against the edge of the head to curl it against the container body, means to cause the crimping roller to travel in a path parallel to the wall of the container body, comprising a guide block having a cam groove, a vertical shaft and a pair of arms mounted thereon, a roller on one of the arms extending into the cam groove, a crimping roller on the other arm adapted 115 to engage the edge of the container head, a vertically movable wedge between said arms, a spring to support the wedge, a foot pedal, and a flexible connector between the foot 120 pedal and the wedge to force the crimping roller against the edge of the head.

3. In a machine for securing heads to container bodies, the combination of means for rotating the container body with the 125

- head thereon, means to support the body comprising a vertically movable post, a table rotatably mounted on the upper end of the post to receive the container, a crimping 5 roller adapted to be pressed against the edge of the head to curl it against the container body, an arm to carry said roller means to cause the crimping roller to travel in a path parallel to the wall of the container body, said means comprising a guide block provided with a cam groove, a pivoted arm and a roller in the end thereof extending into the cam groove, and means for communicating the movement of said arm to the crimping roller comprising a spring held wedge between said arms and a pedal to force down the wedge to separate the arms. 10
5. In a machine for securing heads to container bodies, the combination of means for rotating the container body with a head thereon, means to support the body comprising a vertically movable post, a table rotatably mounted on the upper end of the post to receive the container, a crimping roller 15 comprising a spring held wedge between said arms and a pedal to force down the wedge to separate the arms. 40
4. In a machine for securing heads to container bodies, the combination of means for rotating the container body with a head thereon, means to support the body comprising a vertically movable post, a table rotatably mounted on the upper end of the post to receive the container, a foot pedal, 20 a lever connected thereto, a spring between the lever and the post to press the post upwardly, a crimping roller adapted to be pressed against the edge of the head to curl it against the container body, an arm 25 to carry said roller means to cause the crimping roller to travel in a path parallel to the wall of the container body, said means comprising a guide block provided with a cam groove, a pivoted arm 45 and a roller in the end thereof extending into the cam groove, means for communicating the movement of said arm to the crimping roller comprising a vertically movable wedge between said arms, a spring 50 to support the wedge, a foot pedal, and a flexible connector between the foot pedal and the wedge to force the crimping roller against the edge of the head. 55

BEN K. FORD.
